(57) **CLAIM**

The ornamental design for an electric contact, as shown and described.

DESCRIPTION

FIG. 1 is a bottom, front and right side perspective view of an electric contact;

FIG. 2 is a front elevational view thereof, a rear elevational view being a mirror image of FIG. 2;

FIG. 3 is a left side elevational view thereof;

FIG. 4 is a right side elevational view thereof;

FIG. 5 is a top plan view thereof;

FIG. 6 is a bottom plan view thereof;

FIG. 7 is a bottom, rear and right side perspective view of component 1 of the electric contact;

FIG. 8 is a front elevational view thereof;

FIG. 9 is a rear elevational view thereof;

FIG. 10 is a left side elevational view thereof;

FIG. 11 is a right side elevational view thereof;

FIG. 12 is a top plan view thereof;

FIG. 13 is a bottom plan view thereof;

FIG. 14 is a bottom, front and right side perspective view of component 2 of the electric contact;

FIG. 15 is a front elevational view thereof;

FIG. 16 is a rear elevational view thereof;

FIG. 17 is a left side elevational view thereof;

FIG. 18 is a right side elevational view thereof;

FIG. 19 is a top plan view thereof; and,

FIG. 20 is a bottom plan view thereof.

The broken lines shown in the drawings illustrate portions of the electric contact that form no part of the claimed design.

1 Claim, 10 Drawing Sheets
